(57) CLAIM

The ornamental design for a motor car, toy replica and/or other replicas, as shown and described.

DESCRIPTION

FIG. 1 is a left side view of a motor car, toy replica and/or other replicas;

FIG. 2 is a right side view thereof;

FIG. 3 is a top view thereof;

FIG. 4 is a front view thereof; and,

FIG. 5 is a rear view thereof.

The vehicle portions shown in broken lines form no part of the claimed design.
